(57) CLAIM

The ornamental design for a convertible heel with a detachable leg cover, as shown and described.

DESCRIPTION

FIG. 1 is a front perspective view of a convertible heel with a detachable leg cover according to the embodiment.

FIG. 2 is a first side view of the convertible heel with a detachable leg cover of FIG. 1.

FIG. 3 is a second side view of the convertible heel with a detachable leg cover of FIG. 1.

FIG. 4 is a back view of the convertible heel with a detachable leg cover of FIG. 1.

FIG. 5 is a front view of the convertible heel with a detachable leg cover of FIG. 1.

FIG. 6 is a top view of the convertible heel with a detachable leg cover of FIG. 1.

FIG. 7 is a bottom view of the convertible heel with a detachable leg cover of FIG. 1.

FIG. 8 is a back view of the convertible heel with a detachable leg cover of FIG. 1 showing the detachable leg cover unzipped.

FIG. 9 is a front view of the convertible heel with a detachable leg cover of FIG. 1 showing the detachable leg cover unzipped.

FIG. 10 is a back view of the convertible heel with a detachable leg cover of FIG. 1 showing the detachable leg cover opened.

FIG. 11 is a front view of the convertible heel with a detachable leg cover of FIG. 1 showing the detachable leg cover opened.

FIG. 12 is an exploded front perspective view of the convertible heel with a detachable leg cover of FIG. 1.

FIG. 13 is an exploded first side view of the convertible heel with a detachable leg cover of FIG. 1.
 FIG. 14 is an exploded second side view of the convertible heel with a detachable leg cover of FIG. 1.
 FIG. 15 is an exploded back view of the convertible heel with a detachable leg cover of FIG. 1.
 FIG. 16 is an exploded front view of the convertible heel with a detachable leg cover of FIG. 1.
 FIG. 17 is an exploded back view of the convertible heel with a detachable leg cover of FIG. 1 showing the detachable leg cover unzipped; and,
 FIG. 18 is an exploded front view of the convertible heel with a detachable leg cover of FIG. 1 showing the detachable leg cover unzipped.
 The broken lines in the figures depict portions of the convertible heel with a detachable leg cover that form no part of the claimed design.
